CLAIM

The ornamental design for a lighting structure for repelling animals, as shown and described.

DESCRIPTION

FIG. 1 is a perspective view of the lighting structure for repelling animals in accordance with the invention; FIG. 2 is a front view thereof, the rear view being a mirror image thereof;

FIG. 3 is a left side view thereof, the right side view being a mirror image thereof;

FIG. 4 is a top view thereof; and,

FIG. 5 is perspective view thereof shown on a railing.

The broken lines shown in the drawings illustrate portions of the lighting structure for repelling animals and environmental structures that form no part of the claimed design. The jagged lines in the drawings indicate the design has no specific length.
